TIRE

Earle W. Hawkinson, Minneapolis, Minn., assignor to
Paul E. Hawkinson Company, Minneapolis, Minn., a
corporation of Minnesota

Application April 6, 1954, Serial No. 29,883

Term of patent 14 years

(Cl. D90—20)

Fig. 1 is a view in elevation of a tire showing my new design; and

Fig. 2 is a fragmentary transverse section taken on the line 2—2 of Fig. 1.

The dominant features of my invention reside in those portions shown in full lines.

I claim:

The ornamental design for a tire, as shown and described.
